UNITED STATES PATENT OFFICE.

DAVID GESSNER, OF WORCESTER, MASSACHUSETTS, ADMINISTRATOR OF ERNST GESSNER,
DECEASED.

CARDING-ENGINE.

No. 920,862.

Specification of Letters Patent.

Patented May 4, 1909.

Original application filed March 26, 1895, Serial No. 543,205. Divided and this application filed July 28, 1900.
Serial No. 25,088.

To all whom it may concern:

Be it known that I, DAVID GESSNER, a citizen of the United States, residing at Worcester, in the county of Worcester, State of 5 Massachusetts, have been duly appointed administrator of the estate of ERNST GESSNER, deceased, late of Aue, in the Kingdom of Saxony, Germany, who in his lifetime did invent certain new and useful Improvements 10 in Carding-Engines, of which the following is a specification.

The present application is a division of the application filed by the said Ernst Gessner on March 26th, 1895, Serial No. 543,205, on 15 which application Letters Patent of the United States were granted on August 21st, 1900, No. 656,402.

The present invention relates to carding engines, and has for its object to produce an 20 efficiently acting carding engine, which will not be subject to objectionable clogging of the card clothing.

In carding engines heretofore proposed, the arrangement of the workers with respect 25 to the swift and the mode of working the same have the disadvantage that the remnants of the fleece and foreign matters remain in the card clothing of the workers. In this manner the card clothings become gradually clogged and unfit for a regular even distribution, because the card clothing, when in a filled condition, operates upon the fleece in a manner different from the manner in which it would operate if clean, and of course in the 30 intermediate stages of filling would operate differently. It will be seen, therefore, that the production will be uneven. In order to remedy this defect it has heretofore been necessary to stop the operation of the machine and clean the card clothing. This, of course, causes delay and even if the hand card be employed to effect the cleaning of the card clothing, the working of the machine is disturbed.

45 The object of the present invention is to overcome these disadvantages.

According to this invention, there is employed a stripper or transfer roller, which intervenes between two workers having 50 hook-like teeth to effect the transfer of a fleece from one worker to another, whereby the workers are not only constantly cleaned, but the upper and less loosened fleece layer taken by the last worker from the swift is 55 carried as a continuous compact layer on the

outside of the rollers from worker to worker and brought back to the swift for another working. The new stripper or transfer roller, as it will be herein designated, is provided with brush-like card clothing having the points rearwardly directed or inclined with respect to the direction of motion of the roller. This roller engages in the card clothing of the workers, the teeth of which are also rearwardly directed with respect to the direction of rotation of the workers, and the workers and transfer rollers are run at the same or substantially the same surface speed, so that the card clothing of the two working parts will run in opposite directions at their 60 points of contact, at substantially the same rate of speed. The new transfer rollers are also in instances so arranged that they come into working proximity with the swift or drum, so that they serve as workers therefor. 65

In the accompanying drawing is shown diagrammatically several carding engines embodying the said invention. It will be understood, however, that the various structures shown in the figures may be used 70 singly or combined on a single engine. 75

In the drawing—Figure 1 shows a single worker and a single transfer roller; Fig. 2 a plurality of workers and a transfer roller; Fig. 3 a somewhat similar arrangement; and 80 Figs. 4, 5 and 6 modifications of the same general idea.

In all the figures A represents the drum or swift, B the worker, C the new stripper or transfer roller and D the strippers.

In Fig. 1 the stripper or transfer roll C which turns in the direction of the arrow, has its teeth rearwardly directed with respect to its direction of motion and enters among the teeth of the worker B whose teeth 90 are likewise rearwardly directed with respect to their direction of motion. The transfer roll C runs at the same or substantially the same surface speed as the worker, so that the teeth of the transfer roll and of the worker 95 move opposite to each other at their points of contact at substantially the same surface speed. The transfer roll C is located near to the drum A and owing to its position it can act in a twofold manner, that is to say, to return the fleece which it has taken from the worker B to the drum A at its outer side and at the same time, owing to the inclination of its teeth, take up from the main cylinder or drum A a certain portion of the material at 100 105 110

its inner side, which is then deposited on the surface of the worker B and afterward returned again to the main cylinder, so that in this arrangement the transfer roll serves as a stripper for the worker and at the same time as a worker for the drum or main cylinder. These transfer rollers have teeth of a greater length than the length of the teeth against which they operate. An additional transfer 10 roller C' may be arranged to operate upon the worker. This transfer roller is similar to the transfer roller C and is driven at substantially the same speed as the worker.

In the construction shown in Fig. 2, the 15 transfer roll C is arranged between two workers B, the teeth of the said transfer roll entering among the teeth of both workers. The transfer roll in this construction is arranged near the drum. The two workers B 20 and the transfer roll C rotate in the same direction so that the adjacent or coöperating card surfaces are moving at their point of contact in directions opposite to each other, whereby the material delivered up by the 25 lower worker B to the transfer roll C on its outer side is carried by it in a direction opposite to that of the drum's rotation and is delivered up to the upper worker, from whence it is returned to the drum. The 30 transfer roll thus acts as a worker for the drum at its inner side, transferring the material from the upper worker to the drum and taking up a fresh portion of material, giving it to the lower worker which returns it to the 35 drum, the material being carried in the direction of the drum's rotation.

In Fig. 3 I have shown an arrangement of workers similar to that in Fig. 2, but in this case the transfer roll does not serve as a 40 worker for the drum, but carries material from one worker to the other both on its inner and its outer side. I have also shown a 45 stripper D in this figure, which stripper may, however, be omitted.

In Fig. 4 I have shown a number of transfer 50 rolls and workers alternately arranged about the drum and close to one another so that the teeth of one roller enter between the teeth of the following roller, the surface speed 55 of the transfer rollers being substantially the same as that of the workers. The fleece is worked at the inner side of the rollers, each roller taking up a portion of the fleece from the drum and stripping the fleece from the adjacent roller to be transferred to the drum again, thus carrying the material being worked at 60 the inner side of the rollers in the direction of the drum's rotation. The lowermost worker takes up a portion of the fleece from the 65 drum, which fleece is then carried from one roller to the other at their outer side in a direction opposite to the drum's rotation until this fleece reaches the first or upper roller C which returns it to the drum. Upon 70 examining the material lying upon and

among the teeth of the surface of the drum, it is found that the coarser part or less worked portion of the fiber forms the upper layer on the drum and it is by this arrangement that this portion of the fiber is taken up by the last roll of the series, and carried back to the first roller to be worked once more on the drum. In this arrangement the transfer rollers act as workers for the drum and the workers act in the same manner in 75 so far as each of them strips the material from the adjacent transfer roll and carries it to the next following roller.

In Fig. 5 I have shown a worker coöperating 80 with the drum, a transfer roll located close to the worker so as to remove fleece therefrom, and a stripper for returning the material to the drum.

In Fig. 6 I have shown a series of workers, 85 transfer rolls and strippers located between the workers. The action of this modification is similar to that shown in Fig. 4. It will of course be understood that the various forms of the invention which I have shown and described are illustrative merely and that I 90 do not confine myself thereto.

It will be understood that in all the constructions shown and described the teeth of the transfer roller enter between the teeth of the carded surface with which it coöperates, and by reason of the disposition of the various teeth and the relative movement of the surfaces, the teeth of working rollers or other carded surfaces which coöperate with the transfer roller will be continuously ground or sharpened in such a manner that they become needle - pointed, so that periodical grinding of the teeth, as heretofore, is unnecessary.

Having described this invention, what I 105 claim and desire to secure by Letters Patent is:

1. In a carding engine, the combination of a moving card surface, two card-surfaced rolls having hook-like teeth in operative relation to said moving card surface, and a transfer roller having brush-like teeth which are rearwardly directed with respect to their direction of motion, in operative relation to both of said card-surfaced rolls, said transfer roller rotating in a like direction to that of at least one of said card surfaced rolls.

2. In a carding engine, the combination of a moving card surface, two card-surfaced rolls having hook-like teeth in operative relation to said moving card surface, at least one of said card surfaced rolls having teeth which are rearwardly directed with respect to their direction of motion, and a transfer roller having brush-like teeth which are rearwardly directed with respect to their direction of motion, in operative relation to both of said card-surfaced rolls, said transfer roller rotating in a like direction to that of said card- 130

surfaced rollers which has rearwardly directed teeth.

3. In a carding engine, the combination of a moving card surface, two card-surfaced rolls having hook-like teeth in operative relation to said moving card surface, and a transfer roller having brush-like teeth which are rearwardly directed with respect to their direction of motion, in operative relation to both of said card-surfaced rolls, said card-surfaced rolls and transfer roller rotating in the same direction.

4. In a carding engine, the combination of a moving card surface, two card-surfaced rolls having hook-like teeth which are rearwardly directed with respect to their direction of motion, in operative relation to said moving card surface, and a transfer roller having brush-like teeth which are rearwardly directed with respect to their direction of motion, in operative relation to both of said card-surfaced rolls, said card-surfaced rolls and said transfer roller rotating in same direction.

25 5. In a carding engine, the combination of a moving card surface, two card-surfaced rolls having hook-like teeth in operative relation to said moving card surface, and a transfer roller having brush-like teeth which are rearwardly directed with respect to their direction of motion, in operative relation to said moving card surface and both of said card-surfaced rolls, said card-surfaced rolls and said transfer roller having the same direction of rotation.

35 6. In a carding engine, the combination with the drum, of card-clothed rollers, to-

wit: transfer rollers having brush-like card clothing and workers having hook-like teeth, arranged about the drum alternately and in series and in contact with one another and with the drum, so that the teeth of one roller will enter between the teeth of the following roller and of the drum, all having their teeth rearwardly directed with regard to their direction of motion, means for driving the same in such directions that the contacting card surfaces of the said rollers shall be moved in opposite directions to each other and at the same or nearly the same surface speed, so as to act as transfer rollers to strip the material one from another in an unbroken sheet and carry it at their outer side in direction opposite to the drum's rotation from the last roller of the series to the first of the series, to be thence returned to the drum, substantially as described.

7. In a carding engine, the combination of a moving card surface, a card-surfaced roller having hook-like teeth rearwardly directed with respect to its direction of rotation, and in operative relation to said moving card surface, and a transfer roller having brush-like teeth which are rearwardly directed with respect to their direction of motion and which enter between the teeth of said card-surfaced roller, said card-surfaced roller and the transfer roller both rotating in the same direction.
